US00D721736S

(12) **United States Design Patent**
Park

(10) **Patent No.:** **US D721,736 S**
(45) **Date of Patent:** **** Jan. 27, 2015**

(54) **DISPLAY SCREEN OR PORTION THEREOF
WITH ICON**

(71) Applicant: **Samsung Electronics Co., Ltd.,**
Suwon-si (KR)

(72) Inventor: **Sang-Hyun Park**, Seoul (KR)

(73) Assignee: **Samsung Electronics Co., Ltd.,**
Suwon-si (KR)

(**) Term: **14 Years**

(21) Appl. No.: **29/459,907**

(22) Filed: **Jul. 4, 2013**

(30) **Foreign Application Priority Data**

Jan. 9, 2013 (KR) 30-2013-0001417

(51) **LOC (10) Cl.** **14-04**

(52) **U.S. Cl.**

USPC **D14/492**

(57) **CLAIM**

The ornamental design for a display screen or portion thereof icon, as shown and described.

DESCRIPTION

FIG. 1 is a front view of a display screen or portion thereof with icon, showing my new design; and,
FIG. 2 is a front view thereof, but with environment shown in broken lines.

The display screen or portion thereof shown in broken lines forms no part of the claimed design.

1 Claim, 2 Drawing Sheets

FIG. 1

FIG. 2
